UNITED STATES PATENT OFFICE

OSCAR H. PIEPER, OF ROCHESTER, NEW YORK

DENTAL SPRAY

Application filed May 16, 1927. Serial No. 191,635.

This invention relates to sprays and particularly to a mouth spray for use by members of the dental profession.

During the course of the usual dental operations upon teeth within the mouths of patients, it is frequently necessary to use a spray of liquid to remove small particles of teeth, amalgam and other substances from cavities in the teeth and from between the teeth and cheeks. As the nerves of the teeth are very sensitive to changes of temperature it is necessary to use a washing or flushing liquid which has been heated to approximately normal body temperature. According to some of the older practices hand syringes which were filled when necessary from open vessels containing heated water were used. This method was not entirely satisfactory as it was difficult to maintain the water in the open vessels at uniform temperatures, and the filling of the syringes satisfactorily required considerable time. Also, considerable time was required for maintaining a supply of fresh water in the vessels, and since the syringe and water container were separate articles, it was frequently the case that one or the other was not immediately available when needed.

Since it is highly desirable that dental operations be completed as quickly as possible, the tendency in later years has been toward the development of apparatus which is compact and efficient and which may be placed within easy reach of the dentist. Accordingly, sprays comprising closed containers which may be connected directly to a source of water supply, automatically controlled means for heating the water in the closed containers, and flexible tubes having spray heads thereon for conducting the heated water from the container have been provided. In the usual form of such apparatus the flow of water is controlled entirely by a small valve positioned in the spray head, and the spray head when not in use is placed in a rack or holder on some part of the apparatus stand or support. Owing to the fact that the valve in the spray head must be of the type which can be quickly opened and closed, it has been found to be difficult if not impossible

to provide such a valve which can withstand the pressure of the usual water line without leaking. Consequently there may be a continual drip from the spray head to the floor when it is supported in its inoperative position on the stand or support. It has been found, also, that even when there is no leakage from the spray head due to pressure from the water line, there is a slight drip from the discharge end of the spray head for a short time after it has been used. In some cases containers have been placed on the floor of the operating room to catch the drip and in other cases it has been allowed to fall upon the floor. In either case the result achieved is unsightly.

An object of this invention is to provide an apparatus of the above type in which means have been provided for removing the pressure from the spray head valve when the spray head is not in use. Another object is to provide improved means for supporting the spray head when it is not in use. Another object is to provide improved means for receiving the drip from the spray head. Another object is to provide a spray device which is compact, efficient, and dependable in use.

Other objects will be in part obvious or in part pointed out hereinafter.

The invention accordingly consists in the features of construction, combinations of elements and arrangements of parts as will be exemplified in the structure to be herein-after described and the scope of the application of which will be indicated in the following claims.

In the accompanying drawings in which is shown one of the various possible embodiments of this invention,

Figure 1 is an elevation of the complete spray device;

Figure 2 is a plan view of the device shown in Figure 1; one position of the spray head holder being shown in dotted lines;

Figure 3 is a view showing the manner in which the spray head is supported;

Figure 4 is a sectional plan view of the outer end portion of the spray head holder;

Figure 5 is a plan view of the container

with part of the upper wall broken away to show the inlet and outlet passages;

Figure 6 is a view taken substantially on line 6-6 of Figure 2, the view being distorted to show the parts in a single plane; and

Figure 7 is a fragmentary sectional view through the top or cover portion of the container, showing the main valve for controlling the flow of water through the device.

Similar reference characters refer to similar parts throughout the several views of the drawings.

Referring now to the drawings in detail, there is shown a spray device comprising a cup-shaped member 10 having a cover 11 provided with inlet and outlet passages, a flexible tube 12 forming a discharge conduit for the container, and a spray head 13 mounted on an end of the flexible tube 12.

The open end of the cup-shaped member 10 is threaded to receive a threaded annular flange 14 which depends from the cover member 11. The portion 10 of the assembled container is adapted to be received within the cylindrical heating member 15 which is of usual construction and provided with the usual heat controlling means. The member 15 is provided with a bracket 16 by means of which it may be supported in any convenient position.

The cover member 11 is provided with inlet and outlet passages 17 and 20 between its upper and lower surfaces. A nipple 21 extends through the lower wall of the passage 17 and provides means for connecting the container with a source of water supply through the flexible tube 22. A second nipple 23 extends through an opening in the bottom wall of the passage 17 and it is so positioned and of such a length that it normally extends within the member 10 to a point adjacent the bottom thereof. Cold water, as it enters the container, is thus conducted to its natural place at the bottom.

A nipple 24 provides means for attaching the flexible tube 12 to the device in such a manner that it communicates with the outlet passage 20. An opening 25 provides means of communication between the member 10 and the passage 20. An annular ridge 26 surrounding the opening 25 provides a seat for a valve 27 which is mounted in an opening in the upper wall of the passage 20 which is substantially concentric with the opening 25.

The annular flange 28 is threaded to receive the member 29 in which the valve stem 30 is threaded, said annular flange taken with the cover 11 forming a casing for the valve 27. The packing gland 31 is provided for preventing leakage. The valve stem extends above the cover 11 and has a spray head supporting member 32 which also serves as an

operating lever or handle for the valve 27 fixed on its free end portion. The outer end portion of the spray head support is bifurcated and recessed to receive the spray head. The inwardly extending flange 33 is adapted to engage the flange 34 on the spray head.

The spray head is of usual construction being provided with the usual tip 35 and a valve which may be opened by downward pressure of the thumb on the member 36. When the spray head is in its normal position on the supporting member 32 the discharge end of the tip 35 is positioned above the central portion of the cover 11 and the drip therefrom will fall upon the said cover. For collecting the drip, an annular ridge 37 is formed on the cover. The ridge 37 confines the drip to the top of the cover and since the cover is heated through contact with the water within, any water which gathers in the recess formed by the ridge 37 will quickly evaporate.

In Figures 1 and 2 the spray head is shown in its inoperative position on the supporting member 32, and Figure 6 shows the position of the valve 27 when the supporting member 32 is in the position shown in Figures 1 and 2. When it is desired to use the spray head, the operator may grasp the handle 40 and move the spray head upwardly and to the right. The supporting member will thus be moved a quarter turn to the position shown in dotted lines in Figure 2, rotating the valve stem 30 and moving the valve 27 to the open position shown in Figure 7, the full and dotted line positions of the supporting member indicating that the valve is in closed and open positions respectively. When the valve 27 is in the position shown in Figure 7, the passage 20 communicates with the interior of the container and water may be caused to flow through the spray head when the spray head valve is opened by pressure on the thumb member 36. In replacing the spray head in its support, the support is returned to the position shown in Figures 1 and 2, moving the valve 27 into contact with the valve seat 26 and thereby cutting off the pressure of the source of water supply from the spray head valve.

From the foregoing, it will be seen that there is herein provided a device which embodies the features of this invention and achieves the objects thereof. A spray device has been provided which is thoroughly efficient and dependable in use; by means of which a constant supply of heated water may be kept conveniently available; and in which the usual drip due to water line pressure has been eliminated and any water which drips from the discharge end of the spray will be collected and quickly evaporated.

As many possible embodiments may be made of the above invention, and as many

changes might be made in the embodiment above set forth, it is to be understood that all matter herein before set forth or shown in the accompanying drawings is to be interpreted as illustrative and not in a limiting sense.

I claim as my invention:

1. In a device of the class described, a container having a drip catching portion, a conduit for connecting said container with a source of water supply, a conduit forming an outlet for said container, a valve for regulating the flow of water through said outlet, a flexible tube connected at one end to said outlet conduit, a nozzle connected to the other end of said flexible tube, and a nozzle holder operatively connected with said outlet valve, said holder serving to support the nozzle in position to discharge into said drip catching portion.

2. In a device of the class described, a closed container, an inlet conduit communicating with the lower portion of said container, an outlet conduit communicating with the upper portion of said container, a flexible tube connected at one end to said outlet conduit, a spray head connected to the other end of said flexible tube, a valve positioned between said container and the discharge end of said spray head, means for supporting the discharge end of said spray head above said container in spaced relation thereto, and a ridge formed on the upper surface of said container and providing a recess for the reception of the drip from the discharge end of said spray head.

3. In a device of the class described, a container having a part provided with an outlet passage, said part having a drip catching portion thereon, a valve for opening and closing said passage mounted on said part and having an end of its stem projecting from the latter, a flexible tube communicating at one end with said outlet passage, a nozzle mounted on the other end of said flexible tube, and a nozzle holder mounted on the projecting end portion of said valve stem, said holder serving to support the nozzle in position to discharge into said drip catching portion.

4. In a device of the class described, a container having a cover provided with an outlet passage, a valve for opening and closing said passage mounted on said cover and having an end of its stem projecting above said cover, a flexible tube communicating with said passage, a spray head mounted on an end of said flexible tube, a valve operating member mounted on the projecting end portion of said valve stem and having a portion adapted to support the discharge end of said spray head above said container cover, and an annular ridge formed on said container cover to provide a recess for receiving the

drip from the discharge end of said spray head.

5. In a dental spray, the combination of a closed reservoir having an inlet for fluid under pressure and an outlet, of a flexible tube attached to the outlet, a nozzle attached to the flexible tube and having a self-closing valve, said reservoir having a catch basin on its top, and a bracket on the reservoir adapted to cooperate with the nozzle to position the nozzle over the basin.

6. In a dental spray, the combination of a closed reservoir having an inlet for fluid under pressure, and an outlet, of a flexible tube attached to the outlet, a nozzle attached to the flexible tube and having a self-closing valve, said reservoir having a catch basin on its top, a bracket on the reservoir adapted to cooperate with the nozzle to position the nozzle over the basin, and a master valve for said nozzle associated with and operated by said bracket.

7. In a device of the class described, the combination of a liquid holding reservoir having a closure provided with inlet and outlet passages, the inlet passage terminating adjacent the bottom of the reservoir and the outlet passage leading from a point adjacent the top of the reservoir, a flexible conduit connected with the outlet passage, a nozzle attached to said conduit, a valve on the closure for regulating the flow of liquid through said outlet passage, an operating member movable to effect control of the valve, said operating member being designed to releasably support the nozzle, the latter being movable in opposite directions to and from engagement with the operating member and being adapted during movement in one of said directions to be moved in a different direction to effect movement of the operating member and consequent movement of the valve to either open or closed position.

8. In a device of the class described, the combination of a liquid holding reservoir having a closure on its upper end provided with an outlet, a flexible conduit connected with said outlet, a nozzle attached to the conduit, a valve on the closure for regulating the flow of liquid through the outlet, an operating member for the valve arranged to swing between predetermined positions to open and close the valve, said operating member having a portion thereon for releasably supporting the nozzle, the latter having a handle portion arranged to be gripped by the operator for moving the nozzle to and from engagement with said operating member and also having a portion for moving the operating member in opposite directions to open and close the valve subsequent to movement of the nozzle into engagement with the operating member and before movement of the same to release position.
